TYPEWRITING MACHINE

William A. Dobson, Wethersfield, Conn., assignor
to Underwood Elliott Fisher Company, New
York, N. Y., a corporation of Delaware

Application November 22, 1935, Serial No. 51,097

25 Claims. (Cl. 197—63)

This invention relates to a combined margin and tabulator mechanism, and is shown embodied in an Underwood portable typewriting machine.

5 Stops of novel construction are employed for both margin controlling and tabulating.

The novel stop, when in one position, engages a margin counter-stop which may be provided at the center of the machine to limit the movement of the carriage in both directions, thus controlling the writing line-length.

Upon being displaced to another position, the novel combination stop engages a tabulator counter-stop. The use of the novel stop is thus alter- 15 native.

There is effected a substantial reduction in the number of parts and a saving in weight and cost over the application of separate margin and tabulator stop mechanism, especially to portable 20 machine.

It is thus possible to obtain the advantages of both ordinary margin-regulating and columnar or tabulator work.

A conventional braking mechanism can be applied to the carriage of the machine to further reduce the strains on the light machine-frame-work.

Two distinct types of novel combined margin and tabulator stops are shown. The preferred 30 type of combination stop is pivoted on a shaft mounted on the carriage and adjustable about the pivot to control both the margin and tabulating positions of the carriage movement in the discretion of the operator. A rack pivotally 35 mounted on the ends of the stop-shaft laterally letter-spaces the stops, and may also be utilized as a control guide in restoring the stops to their inoperative positions.

A margin-stop-set key and a tabulator-stop-set key may set in motion a novel mechanism for 40 rotating the selected combined stops to their margin or tabulating positions. The stops preferably engage a pair of marginal counter-stops, limiting the carriage movement in both directions. A tabulator counter-stop may also be incorporated to engage the combination stops in 45 their tabulating control position, when a tabulator key on the keyboard is depressed by the operator.

50 The mechanism will rotate the stops to either the margin or tabulating position, regardless of whether the carriage is in its normal or upper-case position.

Alternative types of novel combination stops 55 are disclosed to accomplish this purpose. In a

preferred construction, the stops are pivoted on a cylindrical shaft mounted on the carriage of the machine. Depressing a margin-stop-set key provided on the keyboard of the machine, actuates a system of levers and control arms, which rotate the selected pivoted combination stop about the shaft until a portion of the bottom of the combination stop is in the range of one of a pair of margin counter-stops preferably attached to a lever mounted on the frame of the 10 machine.

At the start of the writing line, one of the combination stops on the left side of the machine, angularly displaced into its margin-control position, as previously described, engages the 15 right margin counter-stop, arresting the movement of the carriage and determining the left margin position of the writing line on the worksheet. The left combination stop in its margin-control position is so constructed as to by-pass 20 the left counter-stop during the rightward movement of the carriage. When the carriage is letter-fed to the finish of a writing line, one of the right combination stops, rotated to its margin-control position by depressing the margin- 25 stop-set lever, as previously described, engages the left counter-stop, which is preferably either forwardly or rearwardly displaced from the right counter-stop, thus arresting the letter-feeding movement of the carriage and determining the 30 finish of the writing line. At the end of the writing line the keys are locked in a known manner, the margin counter-stop lever cooperating in actuating the key-locking device. During the letter-feeding movement of the carriage, the 35 right combination stop in its margin-control position is preferably arranged by novel means to by-pass the right counter-stop.

By depressing a tabulator-stop-set key attached 40 to a lever, which may be operatively connected to the margin-stop-set lever, previously described, the selected combination stop, determined by the position of the carriage at the time, is displaced through a small angle about the stop-mounting shaft, so that the bottom of the stop 45 is in the range of a tabulator counter-stop. When a tabulator-key on the keyboard is depressed, the tabulator counter-stop is moved into the path of the combination stop in its tabulator-control position. The carriage-feed rack may be 50 released in the usual manner, when a tabulator-key is depressed, the carriage being rapidly pulled in the letter-feed direction by a conventional spring-motor, until the selected combination stop in its tabulator-control position engages the tab- 55

ulator counter-stop, arresting the movement of the carriage to determine a tabulating position of a writing line.

A novel stop-rack may be pivotally mounted 5 on the cylindrical shaft, to laterally space and guide the combination stops in some of their various positions. A series of spring detents may be provided to retain the stops in their margin or tabulator control positions, said detents 10 being preferably mounted on the rear of the stop-rack.

The stop-control levers may be arranged to displace the stops into their operative positions, regardless of whether the carriage is in its normal or shifted position, by a novel mechanism 15 consisting of a vertical stop-control lever which may be slidably and pivotally mounted on a shaft, pivotally mounted on the shift-frame at one end, with the opposite end pivotally attached 20 to the fixed machine frame, said lever remaining vertical. When the carriage is shifted the top of the stop-control lever is thus enabled to engage and angularly displace the combination stop in the same manner as when the carriage 25 is in its normal position.

A stop-restorer lever or key may also be provided for rotating the stops into the range of a novel cam or other type of stop-restoring mechanism to rotate the stops to their inoperative 30 positions, out of range of both the tabulator and margin counter-stops when the carriage is moved in the letter-feed direction by releasing the carriage-feed rack from the escapement mechanism by known means. The above stop-rack may cooperate in this stop-restoring operation.

In an optional construction, a novel stop-rack, with a series of slots cut vertically, across the center of the rack, and letter-spaced along its 40 effective length, and a series of notches, in line with said slots, cut across the top and bottom of the rack, may be fixedly attached to the carriage. A series of novel combination stops of the sliding or optional type may be inserted in these slots 45 in the stop-rack, with a novel longitudinal retainer or other suitable device slidably fitted within the rack to retain the combination stops in their respective slots in the rack and to limit the vertical movement of the stops in one direction. The stops may be slotted to provide a spring detent at one side, to frictionally hold the stop within its slot in the rack in some of its operative positions. A shoulder or other suitable means may also be provided on the stop to limit 55 its vertical movement in one direction, the aforementioned longitudinal retainer limiting its vertical movement in the opposite direction.

The stop-control keys are similar to those previously described. When the margin-stop-set 60 key is depressed, it actuates a novel stop-control slide through a system of levers, said slide depressing the selected combination stop within a slot in the rack to the margin-control position where it may engage the corresponding margin counter-stop at the center of the frame, to limit the lateral movement of the carriage in its respective direction and control the length and position of the writing line as previously described.

70 The combination stops on the right side of the rack are preferably slotted to by-pass the right counter-stop while in the margin-control position, during the letter-feeding movement of the carriage. The stops on the left side of the rack 75 may be cut out or slotted to by-pass the left

counter-stop when the carriage is moved in the opposite direction. The right margin counter-stop may be displaced either forwardly or rearwardly of the left margin counter-stop in order to enable it to engage the selected left combination stop in its margin-control position without interfering with the operation of the right combination stops.

Depressing a tabulator-stop-set key causes the stop-control slide to slide the selected combination stop downwardly in the rack through approximately half the distance required for margin-stop operation, into the tabulator-control position. When the tabulator key on the keyboard is depressed, as previously described, a 15 novel type of tabulator counter-stop bracket, pivotally mounted on a shaft attached to the frame, may be rotated into its operative position, with a tabulator counter-stop finger, attached to said bracket in the path of the combination stops 20 in their tabulator-control position, to arrest the movement of the carriage and determine an intermediate or tabulating position thereof.

A stop-restoring key on the keyboard is preferably provided to actuate a novel stop-restoring lever which may engage the bottom of the stops in either their margin or tabulator control positions, and, while the carriage is rapidly moved in the letter-feed direction as previously described, raise the stops within the slots in the rack to 30 their inoperative positions out of range of both the tabulator and margin counter-stops.

Known types of line-end key-lock, line-end key-release and line-end signal may be utilized, the combination stops in their margin-control positions and the margin counter-stop lever respectively co-operating in the control thereof. The conventional type of spring-motor driven carriage, carriage escapement, carriage-feed rack and rack release, as well as carriage-braking 40 mechanism, may also be incorporated in the machine in the usual manner.

The entire construction of this unique device is light, compact, can be applied to a portable machine without altering its general construction, and is so simple in its operation that an operator of ordinary skill can utilize it to its full advantage, thus saving time in performing type-written work requiring indentations or columns of various kinds.

A modified type of combination stop may be incorporated, in which the stop is slidably fitted in a rack fixed to the carriage-end plates. A unique mechanism may also be provided for sliding these stops into one of several operating positions for engagement with either a margin or a tabulating counter-stop by depressing the appropriate control key on the keyboard. A stop-restorer key actuating a series of novel stop-restorer instrumentalities may also be utilized to 60 restore the stops to their normal or inoperative position, out of range of the margin and tabulator counter-stops.

A mechanism for locking the keys at the end of a writing line by the contact of the selected combination stop in its margin-control position with the corresponding margin counter-stop, as well as means for releasing said keys upon the disengagement of said stop from said counter-stop, may also be incorporated, the counter-stop supporting lever co-operating in the actuation of said mechanism.

The usual line-end signal is preferably given when the carriage approaches the end of its writing line, the selected combination stop in its 75

margin-control position actuating said line-end signal instrumentalities. A margin-release mechanism actuated either by a margin-release button at the front of the machine, or a key in the keyboard, may be incorporated to disengage the selected combination stop in its margin-control position by either throwing the margin counter-stop out of engagement with the combination stop, or by utilizing other suitable means, to extend the writing line beyond the established margin position.

Other features and advantages will hereinafter appear.

In the accompanying drawings,

Figure 1 is a rear perspective view of a portable typewriting machine, showing a preferred type of combined marginal and tabulating stops, said stops being pivotally mounted upon the shaft, and also indicating the margin and tabulator set keys, the stop actuating mechanism, and the counter-stops and the stop-restoring mechanism.

Figure 2 is a partial perspective view of the machine of Figure 1, showing the carriage-escapement-release mechanism.

Figure 3 is a perspective view of a portion of the shift-frame and carriage of the machine, showing the carriage-brake mechanism.

Figure 4 is a cross-section through the machine of Figure 1, showing the margin and tabulator stop set keys, the margin and tabulator stop actuating mechanism, and the pivoted combination margin and tabulator stops in their various operative positions, as well as the margin and tabulator counter-stops, in their relative positions with relation to the platen of the machine.

Figure 5 is a rear elevation of the machine of Figure 1, showing the stop-rack, the stop-mounting shaft, with the stops pivotally mounted thereon, also the margin and tabulator counter-stops, and the line-end signal mechanism.

Figure 5^a is a fragmentary perspective view of the disassembled stop-control levers of Figure 5, showing the method of mounting the levers on the shaft.

Figure 6 is a rear perspective view of the stop rack of Figure 1, showing the pivoted combination margin and tabulator stops in various operating positions, together with the stop-restoring mechanism.

Figure 7 is a perspective of the escapement universal bar, showing a portion of the line-end key-lock mechanism.

Figure 8 is a cross-section of a portion of the machine of Figure 4, showing the position of the stop-control lever, with the carriage shifted to the upper-case position.

Figure 9 is a detailed cross-section of a portion of the machine, indicating the margin and tabulator stop set keys in the tabulator-stop-setting position, and showing the pivoted combination stops, the stop-control mechanism and the tabulator-counter-stop in the tabulating position.

Figure 10 indicates the mechanism of Figure 9 with the keys and stops set in the margin-control position, showing the method of engagement of the margin-counter-stops with the pivoted combination stop.

Figure 11 is a partial cross-section of the machine, showing the stop-restoring lever in its operative position with the cam in operation, re-

storing the pivoted stops to their normal positions.

Figure 12 is a view similar to that of Figure 1, indicating a modified type of combined margin and tabulator stops in their various operative positions as well as the margin and tabulator stop set keys, and the stop-restoring key, with their respective actuating mechanisms.

Figure 13 represents a partial plan view of the machine-frame of Figure 12, indicating the method of mounting the stop-control slide.

Figure 14 is a rear elevation of the machine of Figure 12, showing the sliding type of combined margin and tabulator stops in their various operative positions, also the margin and tabulator counter-stops, and the line-end signal mechanism.

Figure 15 is a fragmentary perspective view of the carriage, indicating the method of mounting the tabulator-counter-stop for engaging the sliding combination stops in their tabulating position.

Figure 16 is a partial cross-section through the carriage of Figure 14, showing a sliding combination margin and tabulator stop in its tabulating position, and the method of its engagement with the tabulator-counter-stop.

Figure 17 is a partial cross-section through the machine of Figure 12, indicating the sliding type of combination stop in its normal or inoperative position, in relation to the margin and tabulator counter-stops, as well as the stop-control mechanism.

Figure 18 is a fragmentary elevation of the machine of Figure 12, showing the stop-control mechanism and the sliding type of combination stop in the tabulating position.

Figure 19 is a view similar to Figure 18, showing the stop-restoring mechanism in its operative position.

Figure 20 is a perspective view of the rack of the machine of Figure 12, showing the left and right hand combination stops in various positions, together with the margin-counter-stops and the tabulator-counter-stop for engaging said combination stops.

Figure 21 is a perspective view of the right-hand margin-stop of Figure 20, indicating the stop-locating detent and the clearance slot for by-passing the right-hand counter-stop.

Figure 22 is a view similar to Figure 21, of the left-hand combination stop, indicating the notch at the rear of the stop for clearing the left counter-stop, as well as the counter-stop engaging face.

A laterally slidable carriage 30, Figure 1, is mounted in a case-shift frame 31 of a typewriting machine by the co-operating pairs of runways 32, 33, anti-friction elements 34 being interposed between the carriage and frame runways. A 60 revoluble platen 35 is journaled in the carriage-end plates 36 and 37.

In a preferred embodiment of this invention, a channel-shaped stop rack 38, Figure 6, may be mounted by means of flanges 39 formed at its ends on a shaft 40, extending between the carriage-end plates 36 and 37, behind the platen 35, as indicated in Figures 1 and 6. A pair of screws 41, threaded into the ends of the shaft 40, preferably secure the shaft and stop rack to the carriage-end plates. A collar 42 at each end of shaft 40 is interposed between end plates 36 and 37 and the flanges 39 of the stop rack so as to laterally locate said stop rack.

Two sets of letter-spaced combination margin

and tabulator stops 43 and 44 may be pivotally mounted on the shaft 40, and slidably fitted into a series of letter-spaced slots 38^a cut along the effective working length of the bottom of the stop rack. Each set of stops occupies half the length of the run of the carriage. The stops of the left-hand set, designated by the number 43, are used for margin gaging when returning the carriage to a new line writing position. The right-hand stops, designated by the number 44, are for gaging the right-hand margin when the carriage is running in letter-feed direction. The right-hand stops, also co-operate with end of line signal and key-locking devices as later described. Both sets of stops are also used for tabulating, the position into which a combination stop is set determining its use as a margin gaging or tabulating stop.

In order to set the combination stops in the margin-control position, a margin-set key 45 is depressed, a column 46 upon which said key is mounted moving downwardly to the position indicated in Figure 10. A key-lever 47, pivotally connected to the column 46 by a screw 48, is angularly displaced about a pivot 49 to the position indicated in Figure 10, a shoulder 50 at the bottom of said column 46 resting against a shelf 51 on the base of the machine. A link 52, connected to the upper arm 53 of the key lever 47 displaces a lever 54 at the rear of the machine leftwardly on a shaft 55 journaled in a boss 56 and a bracket 57. A stop-control lever 58, mounted on the opposite end of the shaft 55, as indicated in Figure 5, is angularly displaced rearwardly to the position indicated in Figure 10, the top 59 of the lever 58 rotating the combination stop 44 about the shaft 40 to the margin-control position indicated in Figure 10.

To set the selected combination stops in the tabulator-control position, a tabulator-set key 60 is depressed when the carriage reaches the desired position in its lateral movement, angularly displacing the key-lever 47 about the pivot 49 to the position indicated in Figure 9, the angular displacement being considerably less than that shown in Figure 10 for margin-control operation. As previously described, the angular displacement of the lever 47 rotates the lever 54, thus rotating shaft 55 and moving the stop-control lever 58 rearwardly. The top 59 of the stop-control lever engages a tip 61 at the bottom of the combination stop 43, rotating said stop about the shaft 40 into the tabulating position indicated in Figure 9. The angular displacement of the combination stop from its normal position 55 into its tabulating position, Figure 9, is substantially less than that of rotating it into its margin-control position, Figure 10. As indicated in Figure 9, the angular travel of the key-lever 47, pivotally attached by the screw 48 to the margin-set column 46, is limited by the contact of the extension 62 at the base of the column 46 with the shelf 51 at the base of the machine.

Upon releasing the tabulator or margin stop set key, a spring 63, Figure 10, attached to the key-lever 47, returns said lever, and the keys 45 and 60 to their normal positions, another spring 75, linking lever 47 with the column 46, controlling the angular movement of the margin-set column.

The stop-control shaft 55 is normally mounted in angular relation to the axis of the platen, as indicated in Figure 5. The outer end of the shaft, loosely journaled in the boss 56 formed in the rear plate 65 of the machine frame, is fitted by means of a milled end 67 (Figure 5^a) into a correspondingly shaped slot 68 at the upper end

of the lever 54 and riveted at 69 over said lever or fastened by other suitable means to form a permanent attachment. The opposite end of the shaft 55, substantially at the center of the machine, preferably has two parallel milled flats 70 slidably fitted into a correspondingly shaped slot 71 at the bottom of the stop-control lever 58, in such a manner that the lever 58 may retain its vertical position perpendicular to the platen of the machine regardless of the angular position of the shaft 55. Adjoining said stop-control lever, the shaft 55 is journaled in the bracket 57 attached to a plate 66, attached to the rear plate 64 of shift-frame 31 of the machine. When the carriage is shifted upward by depressing the usual shift-key 73, Figure 4, the bracket 57 displaces the end of shaft 55 through the angle α to the position indicated by a dotted center line in Figure 5. The shifted position of the carriage is illustrated in Figure 8. The rotation of the combination stops 43 and 44 to the tabulating or margin control positions, indicated in Figures 9 and 10 respectively, is accomplished by the stop-control lever 58 in the manner previously described, regardless of whether the carriage is in its normal or upper-case position, as the lever 58 retains its vertical position with its upper end 59 engaging the tips 61 and 74 of the stops regardless of the position of the carriage.

A margin-counter-stop lever 76, Figures 1 and 30 6, formed with two margin-counter-stops 77 and 78 which co-operate with the previously mentioned combination stops to establish the right and left margins respectively, may be pivotally and slidably attached, by means of the screw and slot arrangement 79 and 79^a to an abutment 64^a extending from the rear plate 64 of the carriage-shift frame 31. The counter-stops 77 and 78 are located substantially in the center of the machine. Counter-stop 77 is disposed rearwardly 40 of stop 78, and its contact face 80 is slightly higher than constant face 81 of counter-stop 78.

To start the writing line, the carriage is moved rightward until a shoulder 82 at the bottom of the left combination stop 43 in its margin-control position, as previously described, engages the contact face 81 of the right counter-stop 78. As indicated in Figures 6 and 10, clearance is provided at the front of the combination stop 43 to by-pass the left counter-stop 77. The contact 50 of the left combination stop 43 with the face 81 of the right counter-stop 78 arrests the rightward movement of the carriage and determines the position of the beginning of the writing line.

The combination stops 44 on the right half of 55 the rack are undercut as indicated in Figure 10, to clear the right counter-stop 78 when the carriage is moved leftward. When the writing line is completed, a shoulder 83 of the right margin-stop 44 engages the contact face 80 of the left 60 counter-stop 77, limiting the leftward movement of the carriage and the writing line length.

The stops 43 and 44 after being angularly displaced to any of the operative positions indicated in Figures 9 and 10 are retained in said positions by a series of letter-spaced spring-detents 84, either individually attached or formed by slotting a spring strip 85 mounted on the rear of the rear wall 86 of the stop-rack 38 by any suitable retaining instrumentalities as shown in Figure 5. The spring-detent 84 is formed to engage a notch 87 near the top of the combination stop, retaining the stop in the margin-control position, Figure 10, or the tabulator-control position, Figure 9.

With the selected combination stop located in the tabulating position, as previously described, a tabulator-key 88, Figure 1, is depressed when a tabulating position of the writing line is desired, angularly displacing the tabulator-key lever 89 about a pivot 90 attached to the frame of the machine. The angular displacement of the tabulator-key lever 89 rotates a bell-crank 91 about a pivot 92 at the bottom of the rear plate 65 of the frame by means of a link 93.

A link 94, attached to the free arm of the bell-crank 91, rotates a bail 95, Figure 1, about a pair of pivots 96 on the rear plate 65 of the frame by means of an arm 97, attached to or integral with the lower arm 98 of the bail 95. The contact face 100 of the tabulator-counter-stop lever 101, pivotally mounted on the shift-frame by a screw 102, is raised into the path of the combination stop by the leftward movement 20 of the vertical arm 103 of the bail against an extension 104 at the lower end of the tabulator-counter-stop lever 101.

The leftward motion of the bail 95, through the intermediary of the bail finger 110 engaging an arm 111 of a bracket 112 pivoted to the carriage-shift frame as by screw 113, and a tie-rod 99, Figure 1, linking bracket 112 with a bell-crank 132, Figure 2, pivotally mounted to the shift-frame as at 132^a, rotates said bell-crank 132 rightwardly, so that a roll 132^b, freely mounted on a stud 132^c fixed on the free end of bell-crank 132, will shift the carriage-feed rack 109 out of mesh with an escapement pinion 139 by swinging ears 137 outturned at the ends of said rack 109 rearwardly on pins 140. This releases the carriage from the control of the usual escapement wheel 172 and feed dogs 171 and 174, and permits a spring motor 105 to pull the carriage freely in a leftward direction, until the 40 tip 61 at the bottom of the combination stop 43 in its tabulating position, indicated in Figure 9, engages the contact face 100 of the tabulating counter-stop, arresting the movement of the carriage and determining the tabulating position of 45 the writing line.

To prevent excessive jarring and noise of the impact of the contact of a combination stop 43 or 44 in tabulating position with the face 100 of the tabulator counter-stop lever 101, the speed 50 of the carriage travel is always kept under suitable control by automatically braking the pulling action of the spring motor 105 proportionately to its power. This is accomplished by means of a releasable braking pad 106 of leather or other 55 suitable material co-operating, when the tabulator-key 88 is depressed, with an incline or ramp 107 formed under the base-plate 108 of the carriage, as indicated in Figure 3.

The braking pad 106 is also actuated by the 60 previously described action of the bail 95 and bracket 112.

As indicated in Figure 3, a spring 114 and a link 115 connect the free end of the bracket 112 to toggle links 116, 117. The lower link 116 of the toggle is pivoted on a stud 118 fixed to the rear plate 64 of shift-frame 31, while its upper link 117 is pivoted on a pin 119 to the free end of an arm 120, pivotally mounted on said shift-frame plate at 121 and carrying the braking pad 106. 70 The above braking action, the carriage-propelling spring mechanism and the escapement release mechanism are substantially as described in detail in my Patent No. 1,954,472.

Upon releasing the tabulator-key 88, a spring 75 122, Figure 1, interposed between the tabulator

counter-stop lever 101 and the frame, withdraws the counter-stop contact face 100 from the path of the combination stops in their tabulating position. A spring 123, Figure 3, connecting the lower link 116 of the toggle to the plate 64, restores 5 the link 116 to its normal position, releasing the brake-pad 106 from engagement with the ramp 107 of the carriage.

In order to restore the stops 43 and 44 to their normal or inoperative position, a lever 124 formed 10 integral with or attached to rack 38 is pressed forward, as indicated in Figure 11, until a horizontal flange 125 at the front of the rack 38 engages the upper surface of a flange 126 of a member 127 attached to the usual plate 128 which 15 serves, by co-operating with a bar 128^a mounted between the carriage-end plates, to prevent a rearward displacement of the carriage during the operation of the machine. All of the heads 129 of the previously set stops 43 and 44 are thus 20 brought within the range of a cam 130 mounted substantially at the center of the rear of the machine on the plate 128. It is obvious that when the stop-rack 38 is turned to the Figure 11 position, for stop restoration, it depresses said member 127 to turn the margin counter-stop lever 16, to thereby suppress the margin counter-stops 11, 18 to prevent the latter from interfering with said stop restoration; said member 127 engaging the flange 212 of said counter-stop lever 16. 30

Depressing a carriage-feed rack-control lever 135, Figure 4, pivotally mounted on the platen-shaft 136, angularly displaces a lug 137^a attached to one of the carriage-rack ears 137, said lug 35 slidably fitted in a yoke 138 at the bottom of said lever 135, thus raising the carriage-feed rack 109 out of engagement with the escapement-pinion 139, the lug 137^a rotating the rack about pivots 140. Upon releasing the carriage-feed rack, or letter-feeding the carriage normally, the 40 spring motor 105 draws the carriage leftwardly, the heads 129 of the stops being brought successively into contact with the cam 130, restoring the stops to an inoperative position, indicated in Figure 4. With the heads 129 of the stops in 45 contact with the rear vertical wall 86 of the rack, the combination stops 43 and 44 are out of range of the contact faces 81 and 80, respectively, of the margin counter-stops, as indicated in Figure 4, with the tips 61 and 74 of the stops out of 50 range of the tabulator counter-stop contact face 100. A spring 141, Figure 4, attached to the upper arm of the lever 135 restores said lever to its normal position, throwing the rack 109 into engagement with the escapement pinion 139 when 55 the lever 135 is released, resuming normal letter-feeding of the carriage.

When lever 124 is released by the operator, a torsional spring 131, Figure 6, carried on the collar 42, one end 133 of said spring being attached to the carriage-end plate 37 with the opposite end 134 of the spring attached to the lever 124, rotates the lever and the attached stop rack to their normal positions, indicated in Figure 1, with the combination stops clearing all 65 of the counter-stops.

By suitably locating levers 124 and 135 adjacent to each other, lever 124 could be made to actuate lever 135 automatically if desired, by providing these levers with slidably contacting fingers 124^a 70 and 135^a, as indicated by dotted lines in Figure 4.

In the type-action fragmentarily indicated in Figure 4, depressing a character key 142 displaces a key-lever 143 about a pivot 144 on an extension of the frame. A link 145 connecting the key-lever

to a bell-crank 146 rotates said bell-crank through a small angle about a pivot 147, drawing the type-control rack 148, connected to the free end of said bell-crank, forwardly, thereby moving the type-head 150 toward the platen 35 about a pivot 151 by means of a gear-sector 152 at the hub end of the type-bar 153, said gear-sector meshing with the teeth 154 of the rack 148. A lever 155 pivoted to the upper end of the type-bar 153 may be connected to a momentum-accumulator mechanism, as described in detail in Patent No. 1,908,140, issued to G. G. Going, May 9, 1933, to complete the movement of the type-carrier in approaching its writing position at the platen.

15 A universal bar 156, Figures 4 and 7, for actuating the carriage-escapement mechanism, is operated by the type-bars 153. A projection 157 at the heel of the type-bar 153 engages the top of the universal bar 156 when the type-bar approaches the printing position, thereby depressing said universal bar. Side arms 158 of the universal bar 156, Figure 7, are pivoted at 159 to a pair of bracket-arms 160. A pair of pins 161 inserted at the bottom of the universal bar side arms 158 rearwardly displace the cross-bar 162 of a bracket 163, the vertical arms 164 of said bracket being pivotally attached at 165 to the bracket-arms 160. The rear face 166 of an escapement-dog-control bracket 167 pivotally attached to a lug 168 of the bracket 163 is displaced rearwardly against a stud 170, Figure 4, moving the escapement-dog 171 rearwardly into engagement with the escapement-wheel 172 to letter-feed the carriage, by known means utilized on the Underwood Portable typewriter. The face 166 of bracket 167 may be adjusted relatively to stud 170 by such means as a set-screw 169.

After the key 142 is released, the projection 157 at the heel of the type-bar releases the universal bar 156, and a spring 173, attached to the vertical arm 164 of the bracket 163, angularly displaces said bracket forwardly about the pivot 165 until the vertical arm reaches the pin 161, thus drawing the escapement-dog-control bracket 167 forwardly into its normal position, indicated in Figure 4, with the bracket face 166 out of engagement with the stud 170 attached to the escapement-dog 171, permitting the rear escapement-dog 174 to engage the escapement-wheel 172 and in co-operation with carriage rack 109 and the spring motor 105 to letter-feed the carriage in the usual manner, as the typing operation proceeds.

55 Regardless of which one of the right combination stops 44 is selected for determining the right-hand margin, it is desirable that the usual signal be given as the carriage reaches a point the customary distance from the end of the writing line. During the letter-feeding travel of the carriage, the tip 74 of the selected right combination stop 44 in the margin position engages a finger 175, Figure 5, pivotally attached to a striker-lever 176 in such manner as to permit only a rightward rotation of finger 175. Lever 176 is pivotally mounted on a screw 177, the opposite end of said lever terminating in a striker 178. When the stop 44, in its leftward travel, displaces the finger 175, the striker 178 is raised 70 from a bell 180 at the right side of the rear of the machine, with which bell it is normally in contact, said striker-lever also normally resting against a pin 181 mounted in the bracket 182. As the stop 44 releases the finger 175, a torsional spring 183, connected to the striker-lever 176

and the bracket 182 at the pivot 177, depresses the striker-lever, swinging the striker against the bell and sounding the line-end signal.

In order that the line-end key-lock and key-release may function at the end of a line, regardless of the position of the right combination stop 44 adjusted for right margin-control operation, the counter-stop lever 76 is preferably arranged to co-operate in key-locking and key-releasing, when the selected right margin-stop 10 44 engages the contact face 80 of the left counter-stop. As the carriage continues in its leftward travel, the right combination stop 44 in its margin-control position moves the counter-stop lever 76 leftward by reason of the previously described 15 slot and screw mounting of lever 76. A yoke 185, Figure 1, at the left end of the counter-stop lever engages the upper arm 186 of a lever 187 pivotally mounted on the shift-frame plate 64 by a screw 188. The lower end of the lever 187 rotates a finger 189 through a small angle about a pivot-screw 190 attached to an extension of the frame. The angular displacement of the finger moves a link 191, pivotally connected to the rear of said finger by a pin 192, to the left. The opposite end of the link 191, Figure 7, connected by pin 193 to a universal bar locking lever 194, rotates said locking lever about a pivot 195, the front end 196 of said lever being pressed under a tongue 197 at the bottom of the universal bar 156 into the position indicated by dotted lines in Figure 7. The front end 196 of the lever 194 in engaging the tongue of the universal bar locks said universal bar in its upper position, restraining the projection 157 of the type-bar 153 from depressing the universal bar 156, thus preventing the type-carriers 150 from reaching the platen and thereby blocking the type-keys.

When the carriage is again moved to the right, 40 to start a new writing line, the combination stop 44 releases the contact face 80 of the left counter-stop. A spring 198, Figure 6, attached to a vertical arm 200 of the counter-stop lever 76, withdraws said lever rightwardly, the slot 79 permitting the lever to slide over the screw 79 to the normal position indicated in Figures 1 and 5, the yoke 185 releasing the upper end of the lever 187. A spring 201 attached to the rear end of the universal bar locking lever 194 will then rotate said lever about the pivot 195 to the position indicated in Figure 7. The front end 196 of the lever 194 is thus brought out of engagement with the tongue 197 at the bottom of the universal bar 156, allowing the universal bar to be depressed and permitting the type-carrier 150 to reach the platen when a type-key is depressed.

When it is desired to extend the writing line beyond the established right-hand margin, a 60 margin-release button 202, Figure 4, is pressed, and a tie-rod 203, extending from said button and pivotally connected at its rear end 204 to the bottom of a bell-crank 205, rotates said bell-crank about a pivot screw 206 through a small 65 angle.

The upper arm 207, Figure 5, of the bell-crank 205 rotates the left end of the counter-stop lever 76 about the screw 79 until the upper face 208 of the counter-stop lever is arrested by contact- 70 ing a shoulder 210 at the top of the vertical lever 187. The angular displacement of the counter-stop lever 76 is sufficient to withdraw the contact face 80 of the left counter-stop from the path of the shoulder 83 of the right combination 75

stop 44 in the margin-control position. The writing can thus be continued beyond the established margin position.

Upon releasing the margin-release button 202, Figure 4, a torsional spring 211, interposed between the upper arm 207 of the bell-crank and the shift-frame of the machine at the screw 206, rotates said bell-crank about the screw 206, depressing the horizontal arm 207 out of engagement with the free end of the counter-stop lever 76. The spring 198, connecting the vertical arm 200 of the counter-stop lever to the bracket 182 mounted on the rear frame, withdraws said counter-stop lever 76 to its normal position indicated in Figures 1 and 5, with the counter-stop contact faces 81 and 80 in the respective paths of the combination stops 43 and 44 located in the margin-control position, thus restoring the originally established margin positions.

To limit the angular movement of the counter-stop lever 76 about the pivot-screw 79, a flange 212, Figure 5, extending from the lower edge of the counter-stop lever, may be formed thereon for co-operation with a slot 213 in the plate 66 attached to the shift-frame 31 of the machine. When the counter-stops on the lever 76 are displaced upwardly, the top of the flange 212 may, if the angular movement of the lever is carried far enough, engage the upper edge of the slot 213, thus arresting the upward movement of the counter-stop side of the lever. In the downward movement of the counter-stops, the lower edge of the flange 212 contacts the lower edge of the slot 213, thus limiting the angular movement of the lever 76 in the downward direction.

In incorporating a modified form of combination margin and tabulator stop, as indicated in Figures 12 and 14, a stop-rack 220 may be attached to the carriage-end plates 221 and 221^a, by screws 222 or other suitable means, in a position similar to that previously indicated with reference to stop-rack 38.

Two types of combination stops, a right-hand stop 223, shown in detail in Figure 21, and a left-hand stop 224, shown in Figure 22, may be slidably inserted into letter-spaced slots 230, 231 cut along the effective length of the rack, the width of said slots being substantially equal to the width of the stops. The right-hand stops 223 are preferably located on the right half of the rack 220 with the left-hand stops 224 located on the left half of the rack.

The contour of the left combination stop 224 is substantially the same as that of the right combination stop 223, with the exception of a slot 225 cut at the bottom of the right combination stop 223, to by-pass the right counter-stop 226, Figure 20, during the letter-feeding movement of the carriage, and the notch 227, cut in the rear corner, near the bottom of the left combination stop 224, to clear the left counter-stop 228, during the rightward movement of the carriage.

The rack 220 consists essentially of a rectangular or other suitably shaped tube. A series of letter-spaced slots 230 are cut through the top of the tube with a corresponding set of slots 231 cut through the bottom of the tube in line with said upper notches. These notches extend transversely of the tube, each notch having parallel sides and extending entirely across the width of the rack. Sufficient uncut metal is left between the notches to join the sides 232 and 233 firmly to preserve the rigidity of the tube.

The top slot 230, the companion bottom slot 231

and the opposite sides 232 and 233 of the tube, taken together form an all around guideway which slidably engages the inserted combination stops, the edges 236 and 237 of the stops slidably engaging the inner faces of the tube-sides.

A square or rectangular stop retainer 238, slidably fitted longitudinally in the rack 220, may be inserted into said rack, the sides and bottom of said retainer engaging the corresponding surfaces of a vertical slot 240 cut at the front of the combination stops 223 and 224, to limit the upward movement of said stops. Each combination stop may be detained in any of its operative positions by means of a spring-detent finger 241, formed at the front of the stop as the result of cutting the longitudinal slot 240 close to the front edge of said stop. A pair of projections 242 and 243 are preferably formed on one side of the finger 241 to engage the adjacent wall of the slot 230 in the rack, restraining the movement of the stop in the rack. The finger 241 is generally bent slightly leftward, Figures 21 and 22, this inclination, together with the spring action of the finger and the projections 242 and 243, acting as a detent in holding the stop in its various operative positions.

The margin-control position of the combination stops, as 223, shown in Figure 20, is determined by a shoulder 244 formed near the top of the rear end of the stop which engages the bottom of the upper notch 230 of the rack. The inoperative position of the combination stops, illustrated in Figure 17, is determined by the contact of the bottom 245 of the slot 240 in the combination stop with the bottom face 246 of the stop-retainer 238.

In order to set any of the modified combination stops 223 or 224 in the margin-control position, the carriage having previously been moved to the desired position by the operator, a margin-stop-set key 247, Figure 12, is depressed, a margin-set lever 248, upon which said key is mounted, moving downwardly until the bottom of the lower arm 250 of said lever reaches the upper surface 251 of the base of the frame, or at least until said arm 250 may clear the bottom edge of the key-lever comb-plate. The upper edges of two slots 252 and 253, cut in the vertical column 254 of the lever 248, engage the upper edges of a pair of projecting and vertically extending arms 255 and 256 extending from an adjoining tabulator-set lever 257. The vertical column 254 of the margin-set lever 248 is guided in its longitudinal movement by the co-operation of the side of the tabulator-stop lever 257 and the vertical extensions of arms 255 and 256 extending from said tabulator-stop-set lever.

When the tops of the slots 252 and 253 engage the upper edges of the projections 255 and 256, the tabulator-stop-set lever 257 is angularly displaced downwardly about a pivot-pin 260, attached to the side 261 of the frame. A tie-bar 262, pivoted at its front end to the lower rear end of the tabulator-set lever 257, by a screw 263, moves a bracket 264, attached to or integral with the rear end of said tie-bar, rearwardly, rotating a bell-crank 265, one arm of said bell-crank being pivoted to the bracket 264, by means of a slot 266 in the top of said bracket, said slot engaging a screw 267, attached to said bell-crank arm. The bell-crank 265 is rotated clockwise about a pivot-screw 268, attached to the rear frame of the machine, by the rearward movement of said tie-bar. A link 270, connecting the free arm 271 of the bell-crank 265 to a lower flange

272 of a stop-control lever 273, angularly displaces the bottom of said lever leftwardly about stud 274, attached by means of a post 279 to the rear plate of the shift-frame. As indicated in Figure 18, a heel 275 of the horizontal arm 276 of the stop-control lever 273 engages the top of the lower flange 277 of a stop-control slide 278, depressing said slide. A finger 280, depending from the upper flange 281 of the stop-control slide, engages the top of the selected combination stop 223 or 224, depressing said stop until the shoulder 244, Figure 20, rests upon the bottom of the upper notch 230 in the rack. The selected stops are thus located in the margin-control positions indicated at A and B in Figure 14.

To set a selected combination stop for tabulator operation, a tabulator-stop-set key 282, Figure 12, is depressed, when the carriage reaches the desired position, angularly displacing the tabulator-stop-set lever 257 about the pivot 260. A horizontal projecting arm 283, extending from said lever, engages a slot 284 cut in an extension 285 of the frame of the machine, the sides of said slot 284 acting as a guide for the arm 283 during the downward movement of the lever 257. The angular displacement of the lever 257 by the tabulator-stop-set key is considerably less than that effected by depressing the margin-stop-set key, it being obvious that the extent of said displacement is determined by the arm 250 striking the front of the key-lever comb-plate. It will also be obvious that said projecting arm 283 of the stop-set lever 257 may co-operate to gage the larger displacement of said lever 257 for margin-stop setting. As previously described, the heel 275 at the free end of the horizontal arm 276 of the stop-control lever 273 engages the top of the lower flange 277 of the stop-control slide 278, depressing said slide, the finger 280 at the top of the slide moving the selected combination stop 223 to the tabulating position C indicated by solid lines in Figure 18. It will thus be apparent that the downward movement of the stop from its normal position, to its tabulator-control position, is substantially one-half of that previously indicated for margin-control operation, although these positions may be varied considerably, depending upon the requirements of the design of the machine.

As indicated in Figure 13, the stop-control slide 278 is guided in its longitudinal movement by a pair of guide-plates 286 and 287, attached by screws or other suitable means to the rear plate 128 of the frame of the machine. The inner edges 288 of the guide-plates are beveled, as indicated in Figure 13, with corresponding bevels on the sides 289 of the slide 278, to guide and retain the slide in its longitudinal movement.

Upon releasing the tabulator-stop-set key, a spring 290, Figure 12, connecting the tie-bar 262 to a pin 291, inserted in the frame-side 261, withdraws said tie-bar forwardly, raising the tabulator-stop-set lever 257 and the tabulator-stop-set key to their normal positions. A normally contracted extensible spring 292, connecting the top of the tabulator-stop-set lever 257 to the lower arm 250 of the margin-stop-set lever 248, raises said margin-stop-set lever to its normal position on said lever 257 when the margin-stop-set key is released. It will be obvious that said margin-stop-set lever 248 may simply be hung on said spring 292 in said normal position.

The stop-control lever 273 is maintained in its normal or inoperative position, indicated in Figure 14, by a spring 293, the upper end of which is attached to the fixed stud 274, Figures 12 and 18, with the lower end slidably attached to a shouldered screw or stud 294 inserted near the bottom of the vertical arm 295 of the stop-control lever 273. When the bottom of the arm 295 of the lever 273 is displaced leftwardly by the movement of the margin or tabulator-stop-set keys, the spring 293 is distorted, in a similar direction as indicated in Figure 18. Upon releasing the stop-set keys, the spring 293 tends to resume its normal vertical position, returning the lever 273 to its normal position, indicated in Figure 14.

A torsional spring 299 carried around a screw 309^a in the horizontal arm 276 of the stop-control lever 273, and having one end inserted in or otherwise engaging the flange 277 of stop-control slide 278, retains the slide in contact with the heel 275 of the stop-control lever. The slide 278 is thus brought into its normal position simultaneously with lever 273.

In a manner similar to that previously described with reference to the pivoted type of combination stop, a margin-counter-stop lever 296, formed with two margin-counter-stops, a 25 left counter-stop 228 and a right counter-stop 226, may be pivotally and slidably mounted on the outer end of stud 274 by means of a screw 269 and a slot 269^a, Figure 14. The left counter-stop 228 is located slightly rearwardly of the 30 right counter-stop 226, and the contact faces 298 and 297 of the respective counter-stops are of substantially the same height.

To start a writing-line, the carriage is moved rightwardly until a projection 300, Figure 20, at the bottom of the left combination stop 224, in its margin-control position B, Figure 14, engages the contact face 297 of the right counter-stop 226, arresting the movement of the carriage and determining the left margin position. As indicated in Figure 20, the notch 227 cut in the lower rear corner of the left combination stop 224 permits said stop to by-pass the left counter-stop 228 during the rightward movement of the carriage. Similarly, as indicated in Figure 21, a slot 45 225 is cut at the bottom of the right combination stop 223 to clear the right counter-stop 226 when the carriage is letter-fed.

Upon completion of the writing-line, an extension 301 at the bottom of the rear edge of the 50 right combination stop 223 engages the contact face 298 of the left counter-stop 228, limiting the letter-feed movement of the carriage and determining the writing-line length.

With a selected combination stop, as 223^a, Figure 14, in its tabulator-control position, as previously described, a tabulator key 302, Figure 12, is depressed, when a tabulating position of a writing line is desired, rotating a tabulator-key lever 303, upon which said tabulator key is mounted, about a pivot-rod 304 extending longitudinally across the frame. The lower arm 305 at the rear of the tabulator-key lever, pivotally connected to a tie-bar 306, by a screw 307, moves said tie-bar, rotating a bail 308, pivotally mounted by a pair of screws 309, inserted in the rear of the frame, counterclockwise of Figure 12, by means of an arm 310 extending from the rear end of the tie-bar 306, and pivotally attached to a lower arm 311 of the bail 308 by a screw 312. A finger 313 on the upper arm of the bail engages a depending arm 314 of a tabulator-counter-stop-control lever 315, Figure 15, drawing said lever rightwardly over a pair of screws 316 threaded into the rear plate of the shift-frame, said screws 75

78 normal or inoperative position, indicated in Figure 14.

slidably supporting the lever 315 by means of a pair of slots 317 cut in a horizontal arm 318 of said lever. When the lever 315 is drawn rightwardly, a diagonal slot 320, cut in a bracket 321 at the free end of the counter-stop lever 315, near the center of the machine, engages a finger 322, depending from a tabulator-counter-stop bracket 323. The tabulator-counter-stop bracket 323, pivotally mounted, by means of its bracket-side-arms 324, on a pin 325, supported by a bracket 326, attached to the rear of the shift-frame, is angularly displaced upwardly into the operative position indicated by solid lines in Figure 16 by the camming action of the finger 322 and the slot 320. The release of the carriage-feed rack 109, Figure 17, from the escapement-pinion 139 by known means, as previously described, allows the spring-motor 105 to rapidly draw the carriage leftwardly, when the tabulator-key is depressed. A shoulder 327, Figure 20, at the forward edge of the combination stop 223a in the tabulating position engages a counter-stop finger 328 protruding from the counter-stop bracket 323, thus arresting the leftward movement of the carriage and determining the tabulator-stop position of the writing line.

When the tabulator-key 302 is released, a spring 330, Figure 15, attached to the bracket 321 of the tabulator-counter-stop lever 315, withdraws said lever leftwardly until the vertical arm 314 depending from the right end of the counter-stop lever engages a pin 331 mounted in the shift-frame. The leftward movement of the diagonal slot 320 against the finger 322 causes the counter-stop bracket to move to the position indicated by dotted lines in Figure 16, with the counter-stop finger 328 out of range of any of the combination stops 223 and 224 in the tabulating position.

The braking action of the carriage, to reduce the jarring impact of the contact of the combination stops with the tabulator-counter-stop finger, functions in a manner similar to that previously described, when the tabulator-key is depressed. The vertical arm 314, Figure 12, of the tabulator-counter-stop lever in its rightward movement engages the lower extension arm 111 at the bottom of the bracket 112, thus actuating the brake-control mechanism, as previously described.

In order to restore the combination stops 223 and 224 to their normal or inoperative positions, a stop-restorer key 332 at the right side of the machine is depressed, angularly displacing a stop-restorer lever 333 upon which said key is mounted rearwardly about a pivot 329 attached to the right frame side-member. A tie-bar 334 at the bottom of the machine is moved rearwardly by a screw 335, pivotally connecting the forward end of the tie-bar 334 with the bottom of the stop-restorer lever 333. As the lever 333 is displaced rearwardly, the edge of a slot 336 in the rear end 337 of the tie-bar 334 engages a screw 338 threaded into an arm of a bell-crank 339, rotating said bell-crank about a pivot-screw 340 inserted in the bottom of the frame. The free arm 341 of the bell-crank 339 connected by a link 342 to the lower flange 272 of the stop-control lever 273 angularly displaces said lever rightwardly about the stud 274, raising the horizontal arm 276 of the lever 273 to the position indicated in Figure 19, with a toe 344 of the stop-control lever in the upper or stop-restoring position.

When the carriage is letter-fed in the normal

manner, or the previously described rack-control lever 135 is depressed releasing the carriage-feed rack and allowing the operator to freely move the carriage, the bottoms of the stops 223 and 224 which had been in operative position are brought successively into contact with the toe 344 of the stop-control lever 273 which, by a camming action, slides the stops upwardly in the rack into the inoperative position D, Figure 19, with the stops out of range of the margin counter-stop contact-faces and the tabulator-stop contact-finger.

The torsional spring 299, previously mentioned, retains the stop-control slide against the heel 275 of the stop-control lever when the free end of the arm 276 is raised to any of the upper positions indicated by dotted lines in Figure 18. The finger 280 of the stop-control slide 278 is thus thrown idly out of engagement with the top of the combination stops, when the lever 273 is in its stop-restoring position, as indicated in Figure 19.

The rightward rotation of the vertical arm of the stop-control lever 273, actuated by depressing the stop-restorer key 332, draws the link 270 rightwardly, displacing the bell-crank 265 counterclockwise of Figure 12. The screw 267 in the free end of the bell-crank 265 is moved forwardly along the slot 266 provided in the upper face of the bracket 264 at the rear end of the tie-bar 262, thus preventing the forward motion of the screw 267 from being transmitted to the tie-bar, and allowing the stop-restorer key to be depressed without interfering with the margin or tabulator stop set lever.

The slot 336 is provided at the rear end of the tie-bar 334 at the right side of the machine for a similar purpose. Depressing the margin-stop-set key 241 or the tabulator-stop-set key 232 at the left side of the machine displaces the links 270 and 342 and the lower flange 272 of the stop-control lever 273 leftwardly, as previously described, rotating the bell-crank 339 clockwise. The screw 338 at the free end of the bell-crank 339 slides forward in the slot 336, thus preventing the transmission of the motion of the margin and tabulator control levers to the stop-restorer lever.

When the stop-restorer key 332 is released, a spring 347, one end of which is attached to the rear of the tie-bar 334, the forward end being connected by a pin 348 to the right side of the machine-frame, withdraws said tie-bar forwardly, raising the stop-restorer lever and stop-restorer key to their normal positions.

The line-end-signal device functions in a manner similar to that previously described, the striker 178, bell 180 and finger 175 being the same as those utilized with the pivoted type of combination stop. During the letter-feeding movement of the carriage, the bottom of the selected right combination stop 223, in its margin-control position A, Figure 14, engages the finger 175 attached to the striker-lever 176 pivotally mounted on the screw 177, the opposite end of said lever terminating in the striker 178, as previously described. When the stop 223 displaces the finger 175 leftwardly, the angular movement of the striker-lever 176 raises the striker 178, in opposition to the spring 183, from the bell 180 with which it is normally lightly in contact, a foot 351 depending from said striker-lever, resting against the flange of a fixed bracket 353, holding lever 176 in normal relation to bell 180. As the stop releases the finger 175, the

torsional spring 183, interposed between the striker-lever 176 and the bracket 353 at the pivot-screw 177, brings the striker sharply against the bell, as previously described.

- 5 The type-action, the universal bar and universal bar control mechanism, the line-end key-lock, and key-release and the margin-release mechanisms are similar to those previously described with reference to the pivoted type of combination stops.

10 The right combination stop 223 in its margin-control position, as previously described, engages the contact face 298, Figure 14, of the left margin counter-stop 228 a few letter-spaces before the 15 extreme end of the line. As the carriage continues to move leftwardly in letter-space steps, the counter-stop lever 296 is moved leftwardly, the 20 previously mentioned screw and slot mounting of lever 296 permitting such movement. The leftward movement of the counter-stop lever 296 angularly displaces the vertical lever 187 and, through the instrumentalities previously described, locks the keys through the agency of the universal bar.

- 25 When the carriage is displaced rightwardly, to begin a new writing line, the right combination stop 223, in its margin-control position A, disengages contact face 298 of the left margin counter-stop. The spring 198 linking the vertical arm 30 354 of the counter-stop lever to the bracket 353, attached to the rear of the frame, withdraws said lever rightwardly to the normal position indicated in Figures 12 and 14, the previously mentioned yoke 185 at the left end of the counter-stop lever releasing the upper end of the vertical lever 187. The universal bar is thus released, as previously described, permitting the normal type-bar action.

35 It will be understood that the margin-release 40 button 202 and its associated mechanism, previously described in connection with the pivoted type of combination stops may be used in this construction also, as the key action and locking mechanisms are identical in each case. It will 45 also be understood that the functions of the combination stops are independent of whether the typing operation is carried on in upper or lower case position because of the association of the working parts with the case-shift frame.

- 50 Variations may be resorted to within the scope of the invention, and portions of the improvements may be used without others.

Having thus described my invention, I claim:

1. In a typewriting machine, the combination 55 with a carriage, and a shaft mounted on said carriage, of a plurality of combination margin-and-tabulating stops individually rotatable on said shaft to different operative positions, means, including selectively operable keys, for setting said 60 stops individually to their operative positions for controlling the tabulator-positions and the opposite marginal positions of said carriage, counter-stops operatively engaging said rotatable stops in their opposite margin-control positions, respectively, for arresting the opposite marginal movements of said carriage, and a tabulator counter-stop.

2. In a typewriting machine, the combination 70 with a spring-propelled carriage and a letter-spacing mechanism for said carriage, of a plurality of stops, mounted on the carriage at letter-space intervals, for controlling the opposite marginal and the tabulating positions of said carriage, each stop being settable individually either to a position for arresting the carriage mar-

ginally, or to a different position for arresting the carriage in tabulating, right and left margin counter-stops and a tabulating counter-stop for engaging said stops as margin stops or tabulating stops depending on the setting of said stops, 5 a stop-setter arranged to engage said stops individually, depending upon the letter-space position of the carriage, and means, including selectively operable devices, for actuating said stop-setter differently to set the stops to a marginal position or a tabulating position.

3. In a typewriting machine, the combination with a laterally movable carriage, of a shaft mounted on said carriage, a stop-rack pivotally mounted on said shaft, a plurality of adjustable 15 stops pivotally mounted on said shaft, and guided by said rack, said stops being individually rotatable on said shaft to different settings for controlling the margin and tabulating positions of said carriage, and counter-stops operatively 20 engaging said stops in their margin and tabulating positions, respectively, for arresting said carriage in said margin and tabulating positions, said rack being rotatable on said shaft for rotating the stops into position to co-operate with 25 a stop restoring device.

4. In a typewriting machine having a laterally slid able carriage, a shaft mounted on said carriage, a stop-rack, a plurality of combination margin and tabulator stops spaced laterally from 30 one another by said rack, and pivotally mounted on said shaft, a mechanism for angularly displacing said combination stops about said shaft, into their operative positions, said stops having detenting connections to said rack for yieldably 35 holding said positions, and counter-stop means operatively engaging said combination stops for controlling the margin and tabulator locations of said carriage.

5. In a typewriting machine having a frame, 40 the combination with a laterally slid able carriage on said frame, of a plurality of combination stops mounted on said carriage so as to be settable individually to different postures for controlling the margin and tabulating positions of said carriage, 45 counter-stop-means for engaging said combination stops, including right and left marginal counter-stops laterally separated by a gap, and a stop-setter actuatable to set said stops and disposed on said frame to set any individual combination stop when the latter is registered with said gap by means of said carriage.

6. In a typewriting machine having a letter-feeding and tabulating carriage, the combination 55 of a plurality of combination stops mounted on said carriage so as to be settable individually to different operative positions for controlling the margin and tabulating positions of said carriage, right and left counter-stops and a tabulating counter-stop for engaging said combination stops 60 respectively as margin stops and tabulating stops depending on the setting of said combination stops, a margin-stop-setting key, a tabulating-stop-setting key, a stop-setter, mechanism cooperative with said keys for actuating said stop-setter differently for setting any combination stop, from a neutral position, into one or another of its operative positions, the combination stop that is set depending on the position of the carriage, and means for retaining said stops in 70 their several positions.

7. In a typewriting machine, the combination with a frame and a laterally slid able carriage, of a cylindrical shaft attached to said carriage, a plurality of combination stops pivotally mounted 75

on said shaft, for controlling the margin and tabulating positions of said carriage, a stop-rack pivotally mounted on said shaft for laterally spacing said combination stops, a mechanism 5 angularly displacing said stops into their operative positions, counter-stops operatively engaging said stops for arresting the lateral movements of said carriage at its margin and tabulating positions, and instrumentalities mounted on the 10 frame of said machine for restoring said combination stops to their inoperative positions.

8. In a typewriting machine, the combination with a frame and a laterally slideable carriage, and a cylindrical shaft attached to said carriage, of a 15 plurality of combination stops pivotally mounted on said shaft, for controlling the lateral movement of said carriage, counter-stop means therefor, a mechanism angularly displacing said stops into their margin and tabulator control positions, 20 counter-stops operatively engaging said stops for arresting the lateral movement of said carriage, an instrumentality for restoring said combination stops to their inoperative positions, and means rotating said combination stops about said 25 shaft into engagement with said restoring instrumentality.

9. In a typewriting machine having a laterally movable carriage, a shaft attached to said carriage, a stop-rack pivotally mounted on said 30 shaft, a plurality of combination stops pivotally mounted on said shaft to be rotatable about the latter to different settings for controlling the margin and tabulating positions of said carriage, and a series of letter-spaced slots cut in said rack, 35 laterally locating said combination stops, said rack being rotatable on said shaft to rotate the stops into position to co-operate with a stop restoring device.

10. In a typewriting machine, the combination with a main frame, a case shiftable-frame, 40 a platen-carriage supported on said shift-frame, a complement of stops mounted on said carriage, and selectively settable for predetermining different margin and tabulating positions of said carriage, counter-stop-means for said stops, a setter 45 for said stops, arranged to shift with said shift-frame, a key-mechanism, for said setter, on said main frame, and connecting means arranged to enable said key-mechanism to actuate said setter 50 whether said shift-frame is in its normal or shifted position.

11. In a typewriting machine having a laterally slideable carriage, a hollow rack mounted on said carriage, a series of equally-spaced notches cut 55 transversely through the top of said rack, a corresponding series of notches cut transversely through the bottom of said rack in line with said upper notches, said notches co-operating to form a series of vertical slots through said rack, 60 a plurality of combination stops individually slideable in said slots from a neutral position to a margin position or to a tabulating position, for controlling the margin and tabulating positions of said carriage, counter-stop mechanism having 65 a cooperative alignment with the margin positioned combination stops but having normally no cooperative alignment with the tabulating-positioned combination stops, and a tabulating key operable to bring the tabulating-positioned combination stops and the counter-stop mechanism into cooperative alignment.

12. In a typewriting machine having a laterally slideable carriage, a rack, a series of letter-spaced 75 slots in said rack, a plurality of plate-like combination stops slidably fitted and differently po-

sitionable in said slots for controlling the margin and tabulating positions of said carriage, and counter-stops therefor, each of said combination stops having one of its ends jogged to form relatively offset margin and tabulating stop lugs 5 engageable with said counter-stops.

13. The combination with a laterally reciprocable typing-machine carriage, of a letter-spaced series of combination stops mounted on said carriage so as to be settable individually from 10 a neutral position to one or another of different operative positions, to establish margin stations, or intermediate tabulating stations of the carriage, two, right and left, margin counter-stops for engaging respectively opposite sides of said 15 combination stops in their operative positions, said counter-stops being offset transversely of the carriage path, a tabulating counter-stop, and an actuatable stop-setting device, effective at a plane between said margin counter-stops, whereby, upon initially placing the carriage at a desired right or left margin station, or at a desired intermediate tabulating station, said stop-setting device is effective, upon actuation thereof, to set the appropriate combination stop to one 20 or another of its said operative positions to establish such right or left margin station or intermediate tabulating station.

14. The invention as defined in claim 13, inclusive of a mechanical stop-restoring device 30 common to all the combination stops and actuatable at will to effect restoration of any combination stop, from either its marginal position or from its tabulating position, to a neutral position.

15. The combination with a laterally movable 35 typing-machine carriage, a carriage-movement-limiting stop-device thereon, settable from a neutral position to an operative position, a counter-stop to engage said stop-device, and restoring mechanism conditionable and effective, through 40 lateral movement of the carriage, to restore said stop-device to neutral position, of an operative connection between said restoring mechanism and counter-stop effective to disable said counter-stop while said restoring mechanism is conditioned for 45 restoring said stop-device.

16. The combination with a typing-machine carriage, and a letter spaced series of stops therefor, each stop settable individually from a neutral position to a marginal position or to a tabulating position, of a stop-setter engageable with one or another stop, depending on the letter space position of the carriage, said stop-setter being operable differently for setting said stop to either the marginal or tabulating position, a selectively-operable key-mechanism, including a margin-set key and a tabulator-set key, for operating said stop-setter differently, and counter-stop means for said stops including a counter-stop normally effective to engage the margin-positioned stops. 60

17. In a margin-stop mechanism for a typing-machine carriage, a system of letter-spaced stops individually settable from an idle position to an operative position, said system being divided into 65 two sub-sets of stops, one sub-set being for left-hand margins and the other sub-set being for right-hand margins, a key-operated device adapted to set the stops in either sub-set to operative position by displacement of substantially 70 the same extent from said idle position, the stops having stop-lugs arranged so that any stop set to operative position in one sub-set has its stop-lug offset, transversely of the carriage path, from the stop-lug of any stop set to operative 75

- position in the other sub-set, and two, right and left, counter-stops offset transversely of the carriage path and facing said stops so that one of the counter-stops is individual to one sub-set 5 and the other counter-stop is individual to the other sub-set of said stops.
18. In a typewriting machine, in combination, a laterally movable carriage, a series of letter spaced combination stops mounted on said carriage so as to be settable individually from a neutral position to a position to serve as a margin stop or to another position to serve as a tabulating stop, counter-stop means for said stops and including a margin counter-stop normally 10 effective to engage the margin-positioned stops, a stop-setter engageable with any one of said stops depending on the position of said carriage, said stop-setter being movable to different positions to effect the setting of said stop to its 15 different positions, a margin-set key, a tabulator-set key, and means effective through the operation of one or the other of said setting keys to correspondingly move said stop-setter to one or the other of its different stop setting positions.
19. In a typewriting machine, the combination with a main frame, a case shiftable frame thereon, and a laterally slidable carriage on said case shiftable frame, of a plurality of combination stops mounted on said carriage and individually 20 movable to different positions, for controlling the margin and tabulating positions of said carriage, counter-stops therefor, a slidable stop-setter mounted on said main frame for controlling the movement of said combination stops, and a member on said case shiftable frame operable for controlling the movement of said stop-setter on said frame for locating said stops in their margin and tabulating control positions, said stop-setter being operatively connected to said member so as to 25 case-shift with said member.
20. In a typewriting machine, the combination with a letter-feeding carriage, of a rack on said carriage, a system of key-settable stops mounted on said carriage and disposed at letter-space intervals by said rack, said system of stops being substantially coextensive with the length of the carriage run, a stop-setter, a stop-setting key operatively connected to said stop-setter to set said stops individually to tabulating positions, said system of stops being divided into right-hand and left-hand sub-sets, a margin-key operatively connected to said stop-setter for setting said stops in said sub-sets from normal to margin-controlling positions, a counter-stop movable to position to engage the stops that are set to tabulating position, a counter-stop to engage any marginally set stop in one sub-set of stops to control the right-hand margin on a work-sheet, and a counter-stop to engage any marginally set stop in the other sub-set, for controlling the margin at the left-hand border of the work sheet.
21. In a typewriting machine having a main frame, a shift-frame, a platen-carriage supported on said shift-frame, a plurality of selectively settable combination stops, mounted in letter spaced array on said carriage for controlling the margin and tabulating positions of said carriage, counter-stops to coat with said combination stops, a 60 stop-setter, for said combination stops, mounted to shift with said shift-frame, an actuator for said stop-setter mounted on said main frame, and an operating connection, from said actuator to said stop-setter, arranged to enable said actuator to actuate said stop-setter whether the latter is in its normal or shifted position.
22. In a typewriting machine having a laterally slidable carriage, a system of key-settable stops for said carriage mounted at letter-space intervals, said system including a sub-set of left margin-stops and a sub-set of right margin-stops, a key-operated stop-setter for setting said stops individually relatively to right-hand and left-hand margin-control positions, the left margin stops being offset, transversely of the carriage path, from the right margin stops in the set positions of the stops and a pair of counter-stops, one counter-stop being individual to the left sub-set, and the other counter-stop being individual to the right sub-set, for limiting the opposite marginal movements of said carriage, said counter-stops being offset transversely of the carriage path.
23. In a typewriting machine, the combination with a letter-feeding carriage, of a rack mounted on said carriage, a series of longitudinally letter-spaced slots cut in said rack, and a system of key-settable combination stops slidably fitted in the slots in said rack, each stop individually movable in its slot to different positions for controlling a marginal or a tabulating position of said carriage, counter-stop means, including right and left margin counter-stops, for engaging said combination stops, and a stop-setter differently operable selectively in respect to said different positions for setting a stop for a margin or for tabulating, said carriage being placeable relatively to said stop-setter for selecting the stop preparatory to setting the latter, said stop-setter working in a plane between said margin counter-stops.
24. A key settable margin and tabulating stop mechanism for a typing machine carriage, including, in combination, a series of combination stops mounted at letter-space intervals for individual settings, from an idle position to a margin position or a tabulating position, a margin-set key, a tabulator set key, a single stop-setter, means enabling said keys to actuate said stop-setter differently for margin setting or tabulator setting of a stop, and counter-stop means for engaging said stops for margin or tabulating 40 rest of the carriage, said counter-stop means including a counter-stop normally effective to engage the margin-positioned combination stops.
25. In a margin and tabulating stop-setting mechanism for a typing carriage, a series of combination margin-and-tabulating stops, means supporting said stops at letter-space intervals for individual stop-setting movements, transversely of the carriage, from an idle position to a margin position or to a tabulating position, 45 said stop-setting movements being substantially in the same direction but of different extents from said idle position, a stop-setter, means, including selectively operable keys, for moving said stop-setter differently to set said stops to said 50 margin or tabulating position, and counter-stop means for engaging said stops in their set positions, said counter-stop means including a counter-stop normally effective to engage the margin-positioned combination stops.

WILLIAM A. DOBSON.
